UNITED STATES PATENT OFFICE.

FRANK STRYFFELER, OF DIAMOND, OHIO.

FASTENING DEVICE FOR SHOES.

1,162,663.

Specification of Letters Patent. Patented Nov. 30, 1915.

Application filed September 6, 1912. Serial No. 718,926.

To all whom it may concern:

Be it known that I, FRANK STRYFFELER, a citizen of the United States, residing at Diamond, in the county of Portage and State of Ohio, have invented new and useful Improvements in Fastening Devices for Shoes, of which the following is a specification.

This invention relates to fastening devices for shoes or similar articles, and particularly to a fastening designed for use upon shoes or articles wherein are included overlapping portions such as the adjacent flaps of a shoe, and has for an object to provide a device of this character which can be readily attached to or removed from the shoe and manually set so as to permit of a comfortable overlapping of the shoe flaps across the foot of the wearer.

Another object of the invention is to provide a fastening which will be securely held against casual derangement upon the shoe or accidental loss therefrom.

In the drawing forming a portion of this application, and in which like letters of reference indicate similar parts in the several views:—Figure 1 is a perspective view of a shoe showing the flaps thereof opened and illustrating the application of the fastening thereto. Fig. 2 is a section on an enlarged scale through the flaps showing the companion elements of the fastening engaged. Fig. 3 is a perspective view of one member of one of the elements of the fastening. Fig. 4 is a perspective view of the other member of said element. Fig. 5 is a perspective view of one member of the other element of the fastening. Fig. 6 is a perspective view of the companion member of said other element.

While the fastening is especially designed for use upon shoes, it is evident that the same may be used upon articles of another character wherein two overlapping portions of the article are to be held together as in the adjacent flaps of a shoe. In view thereof, it is understood that the shoe A herein illustrated is merely employed to show one obvious adaptation of the invention.

The element B of the fastening comprises a concavo-convex member 1 and a flat companion member 2, the latter having formed thereon a socket portion 3 which is threadedly fitted in a boss 4 which projects into the concavity of the member 1 as shown.

The main body portion of the member 2 has its central portion projected across one end of the socket to provide a retaining surface 5 for a purpose to be hereinafter explained. 60 The flap D of the shoe lies between the companion members 1 and 2 of the fastening element B the member 2 having a kerf 6 therein to receive a screw driver or suitable tool whereby said member and the companion therefor can be securely adjusted relatively to insure their proper association with the flap. To guard against the causal rotation of the members 1 and 2 on each other, radial notches 7 are formed in the 70 peripheral edge of the member 2, while tongues 8 are formed on the peripheral edge of the member 1. These tongues are adapted to be extended through the flap D and then bent into the notches 7 and then struck 75 up against one side of the member 2 as illustrated in Fig. 2. The element C of said fastening comprises members 9 and 10 which are disposed against the opposite sides of the flap E. The member 10 carries 80 a central threaded stem 11 which adjustably fits in the central neck 12 of the member 9 whereby the latter and said member 10 can be securely confined against the flap as is evident. A kerf 13 in the member 10 may 85 receive a screw driver to facilitate connecting both members upon the flap. Notches 14 similar to the notches 7 are formed in the edge of the member 10 and are adapted to receive the bendable tongues 15 of the 90 member 9. The member 9 has its neck 12 provided with a resilient head 16 which is adapted to accommodate itself in the socket 3 of the member 1 and to expand behind the surface 5 thereof whereby both flaps D and 95 E of the shoe will be positively retained in a closed condition.

The device is simple in construction, inexpensive to manufacture; it may be made of any suitable material that may be found 100 most suitable for the occasion and of a color to harmonize with the color of the article with which it is used, while in practice, it is found reliable, comfortable, attractive and convenient, and of a character whereby it 105 may be removed from one shoe and mounted upon another should such be desired.

I claim:—

A fastening for securing the overlapping portions of an article together comprising a 110 resilient head carrying member adapted to be secured to one portion of the article, a

2
concavo-convex member adapted to be disposed upon the outer surface of the other portion of the article, a hollow threaded boss arranged within the member and depending centrally therefrom, tongues adapted to project through the said portion of the article at diametrically opposite points from said concavo-convex member, a plate adapted to be disposed against the under side of said portion of the article, a socket element rising centrally from said plate and threadedly adjustable within said boss, said plate having peripheral notches for the reception

of said tongues whereby said parts are held associated, and said socket element having 15 relatively large and small aligned communicating bores defining a shoulder therebetween and forming a seat for the resilient head of the first mentioned member.

In testimony whereof I affix my signature 20 in presence of two witnesses.

FRANK STRYFFELER.
